DESIGN FOR A SHOE OR SIMILAR ARTICLE

Samuel L. Kleven, Augusta, Maine

Application May 12, 1944, Serial No. 113,569

Term of patent 14 years

(Cl. D7—7)

To all whom it may concern:

Be it known that I, Samuel L. Kleven, a citizen of the United States, residing at Augusta, in the county of Kennebec, and State of Maine, have invented a new, original, and ornamental Design for a Shoe or Similar Article, of which the following is a specification, reference being had to the accompanying drawing, forming part thereof.

The single figure is a perspective view of a shoe or similar article showing my new design, the opposite side presenting substantially the same appearance as the one shown.

My design for a shoe having its essential features illustrated in full lines on the drawing, is characterized by a narrow perforated trim of a contrasting color to the other parts of the shoe, said trim being sewed to the upper on one side and joined to the insole or platform member on the other side by a lacing of the type and in the manner as shown.

I claim:

The ornamental design for a shoe or similar article, substantially as shown and described.

SAM'L L. KLEVEN.
